(57) **CLAIM**

The ornamental design for a casing for concentrator photovoltaic module, as shown and described.

DESCRIPTION

FIG. 1 is a front view of a casing for a concentrator photovoltaic module showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is a partial view taken along line XXXI-XXXI of

FIG. 3, omitting internal structure for ease of illustration;

FIG. 12 is a partial view taken along line XXXII-XXXII of

FIG. 3, omitting internal structure for ease of illustration;

FIG. 13 is a partial view taken along line XXXIII-XXXIII

of FIG. 3, omitting internal structure for ease of illustration;

FIG. 14 is an enlarged view of XXXIV-XXXIV portion of

FIG. 9;

FIG. 15 is an enlarged view of XXXV-b portion of FIG. 9;

FIG. 16 is an enlarged view of XXXVI-b portion of FIG. 9;

FIG. 17 is an enlarged view of XXXVII-XXXVII portion of

FIG. 10;

FIG. 18 is an enlarged view of XXXVIII-c portion of FIG.

10;

FIG. 19 is an enlarged view of XXXIX-c portion of FIG. 10;

FIG. 20 is an enlarged view of XL-XL portion of FIG. 11;

FIG. 21 is an enlarged view of XLI-XLI portion of FIG. 12;

and,

(Continued)

FIG. 22 is an enlarged view of XLII-XLII portion of FIG. 13.

The dashed broken lines define the bounds of the enlarged partial views of the claimed design and form no part thereof.
